United States Patent Office

Des. 232,637
Patented Sept. 3, 1974

232,637

PORTRABLE TOILET

Howard G. Goldsmith, Cranston, R.I., assignor to Todd
Enterprises, Inc., Providence, R.I.

Filed May 21, 1973, Ser. No. 362,186

Term of patent 14 years

Int. Cl. D23—02

U.S. Cl. D23—48

FIG. 1

FIG. 1 is a front perspective view of a portable toilet showing my new design, showing the cover in a lifted position;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and

FIG. 7 is a bottom plan view thereof.

I claim:

The ornamental design for a portable toilet, substantially as shown.
